his attorneys

UNITED STATES PATENT OFFICE.

EDWARD BARTHOLOMAY, OF ROCHESTER, NEW YORK.

CONNECTOR AND HANGER FOR METERS.

1,282,024.

Specification of Letters Patent. Patented Oct. 22, 1918.

Application filed January 28, 1918. Serial No. 214,207.

To all whom it may concern:

Be it known that I, EDWARD BARTHOLOMAY, a citizen of the United States, and resident of Rochester, in the county of Monroe and State of New York, have invented 5 certain new and useful Improvements in Connectors and Hangers for Meters, of which the following is a specification.

The present invention relates to connecting devices for gas meters and to meter supports associated with such devices, an object 10 of the invention being to provide a connecting device which will connect the inlet and the outlet pipings of the meter without creating any strains in the pipings. Another object of the invention is to provide 15 a hanger associated with such connecting means and adapted to rigidly support the meter from such connecting means.

20 To these and other ends the invention consists of certain parts and combinations of parts, all of which will be hereinafter described, the novel features being pointed out in the appended claims.

25 In the drawings:—

Figure 1 is a front view of a gas meter to which the present invention is shown applied;

Fig. 2 is a section on the line 2—2, Fig. 30 1; and

Fig. 3 is a perspective view of one of the coupling devices used in the intake or inlet piping.

Referring more particularly to the drawings, 35 1 indicates the meter to the inlet 2 of which a piping 3 is connected through a union 4 rotatably mounted on the piping and engaging a screw-threaded portion 5 on a coupling member 6, which, by a short pipe 40 7, is connected to the inlet 2. To the outlet 8 of the meter an elbow 9 is connected by a short pipe 10 and has a piping 11 leading therefrom to the service piping of the house. The elbow 9 is provided with a spherical or 45 ball-shaped surface 12, while the coupling member 6 is provided with a spherical or ball-shaped surface 13. These two coupling members of the inlet and outlet pipings are firmly held against lateral movement by a 50 connector 14 which extends above the meter 1 and has clamps at opposite ends engaging the spherical or ball-shaped surfaces 12 and 13. In this instance, the connector has a central portion to which two opposed clamping jaws 15 are held by a bolt 16 adjustable 55 in the slot 16^a so that the distance between

the two pairs of clamps may be varied, the engaging faces of the jaws being concaved.

A bolt 17 also connects the jaws on the outer side of the piping, so that it is possible 60 by the bolts 16 and 17 to firmly draw the jaws 15 into engagement with the ball-shaped surfaces 12 and 13.

At the extreme ends of each pair of jaws 15 beyond the bolt 17, extensions 18 are provided, which are spaced apart to provide a recess 19. These recesses at the opposite ends of the connector serve to receive the ends of a hanger 20, said hanger, in this instance, being a rigid frame preferably made 70 in one piece and U-shaped in form, its horizontal portion being passed beneath the meter 1 and its arms extending on opposite sides of the meter and through the recesses 19. The extreme ends of the arms are screw- 75 threaded at 21 and on these screw-threaded portions thumb nuts 22 are mounted, the thumb nuts being positioned above the connector so that when tightened they tend to hold the hanger rigidly to the connector 80 against any swinging movement. The coupling members 6 and 9 each have a boss 23 formed with an opening closed by a plug 24. By this arrangement a testing device may be connected to either side of the meter to determine where a stoppage occurs or to take 85 pressure readings.

A connector constructed in accordance with this invention makes it possible to firmly grip the inlet and the outlet pipings 90 after the latter have been connected to the meter. The ball shaped portions on the couplings in the pipings permit such couplings to be gripped by the connector, notwithstanding the fact that the pipings are 95 slightly out of parallelism. This makes it possible to use the connector without placing the inlet and the outlet pipings under any strain, as is necessary when the connector is not adjustably clamped to the pipings. 100 The hanger employed in this invention is simple in construction and is not liable to work loose. Its securing means is situated above the meter where it is not liable to be struck by blows, and at the same time the 105 hanger is secured to the connector in such a manner that all swinging of the meter with reference to the connector is impossible.

What I claim as my invention and desire to secure by Letters Patent is:—

1. The combination with a gas meter, an inlet piping and an outlet piping, of two

- clamps each having two adjustably connected jaws for engaging about one of the piping, and means connecting said two clamps permitting the relative positions of the 5 clamps to be varied.
2. The combination with a gas meter, of an inlet piping provided with a spherical surface, an outlet piping provided with a spherical surface, and a connector having 10 clamps engaging the spherical surface on the two pipings to hold the pipings against relative movement adjacent the meter.
3. In combination with two pipe connections each having a spherical outer surface, a connector having clamps to engage the 15 spherical surfaces of the two pipe connections.
4. In combination with a pipe elbow and a pipe coupling, each formed with a spherical surface, a connector having clamps at 20 opposite ends engaging the spherical surfaces of the elbow and the coupling.

EDWARD BARTHOLOMAY.
